UNITED STATES PATENT OFFICE

ROSCOE D. CONKLIN, OF RAHWAY, NEW JERSEY, ASSIGNOR TO NATIONAL PNEUMATIC COMPANY, OF NEW YORK, N. Y., A CORPORATION OF WEST VIRGINIA

STEP-OPERATED TREADLE SWITCH

Application filed May 12, 1928. Serial No. 277,143.

This invention relates in general to treadle and step operated switches used on vehicles.

One of the objects of this invention is the provision of means for operating the treadle switch employed on vehicles in which the doors are treadle controlled by means of mechanism under the influence of the vehicle step.

A still further object of this invention is to 10 eliminate the necessity of the conventional step switch which heretofore has been wired in parallel to the treadle switch of the vehicle.

A still further object of this invention is the provision of mechanism arranged so that 15 when a person steps on the treadle of a vehicle equipped therewith to open the doors the door opening circuit is maintained when the person steps onto the step.

A still further object of this invention is 20 the provision of mechanism of the above type which is very simple in construction and adapted for economical manufacture and rapid assemblage.

These and other objects are secured by 25 means of this invention.

This invention resides substantially in the combination, construction, arrangement, and relative location of parts, all as will more fully appear hereinafter.

Referring to the drawings, the single figure represents a side elevational view with 30 some parts in cross section showing the combination of elements comprising this invention.

There is known at the present time in this 35 art mechanism whereby the doors of a vehicle may be operated by means of a treadle plate mounted in the platform of the vehicle adjacent the door. This principle of door opera-

tion has been applied to all kinds of vehicles, such as street cars, railway cars, elevated cars, subway cars, and buses. The principle of 40 operation in apparatus of this type is to provide a treadle plate pivotally mounted in the

platform of the vehicle adjacent the doors to be controlled, which treadle plate when depressed by a passenger operates a switch which controls the motor to cause the door 45 to open.

Heretofore in mechanism of this type it

has been necessary to provide a second switch under the control of the step which is pivotally mounted to fold and unfold so that a passenger when stepping from the treadle onto the step will maintain a second switch closed so as to keep the doors open until the passageway is completely cleared of passengers. When the treadle and step are clear the switches open and the door operating mechanism reverses closing the doors.

The object of this invention is to eliminate the step operated switch and substitute therefor a mechanical mechanism which controls the switch on the treadle directly.

To more fully understand the invention 65 reference is now made to the drawings in which the platform of the vehicle has been indicated at 1 provided with an opening therein, the edges of which are protected by means of angle irons shown at 2. Pivotally mounted in the opening in the platform on the rod 4 is a treadle 3 adapted to lie in the same plane as the platform with its front edge adjacent the door slightly raised under the action of a spring (not shown) or other 70 suitable device. The door shaft which extends vertically and is mounted for rotation about a vertical axis in the usual well known manner is shown at 5 supporting one section 75 of a door. This invention is, of course, so adapted to be used on double folding doors and, in fact, any type of swinging door or sliding door.

Mounted under the treadle plate is a casing 7 within which is mounted the switch 85 which is adapted to be closed when the treadle is depressed. The switch is of the push button type having, as shown at 8, a push button extending from the casing 7. Supported directly under the push button on the platform or other fixed support is a plate 9 against which the push button 8 contacts when the treadle is depressed. A collar 10 is mounted under the plate 9 and is provided with an opening extending therethrough in alignment with an opening in the plate. Extending vertically through the opening is a rod 11 which is pivotally supported at its lower end at 13 on the lever 12. At 14 is shown a horizontal rotatable shaft which is 100

journalled in two bearings of which only one is shown at 15 as suitably attached to the framework of the car. Attached to the rotatable shaft 14 are the step arms 16 on which the tread 17 is mounted. The arms 16 are secured to the shaft 14 for rotation with it and have extending rearwardly a projection 18 which is adapted to contact with a fixed stop 19 so as to prevent the step from moving past a horizontal position as it swings outwardly in a clockwise direction as it opens. Secured to the shaft 14 is a short arm 20 adapted to rotate with it and provided at its outer end with an adjustable set screw 21, which set screw is adapted to contact with the arm 22 which is attached to the arm 12. A stop 23 suitably attached to a fixed support is shown for limiting the downward movement of the lever 12.

20 The operation of the device follows: When a passenger wishes to alight from the car he approaches the door 6 and as a result steps onto the treadle 3 causing its outer right-hand end to rotate outwardly on the pivot rod 4. This causes the push button 8 to contact with the plate 9 closing a circuit connected to the switch in casing 7 which controls the mechanism for operating the door. 25 In the usual practice this circuit is interconnected with the motorman's control so that the door is not opened until the vehicle comes to a stop. The closing of the switch on the treadle causes the door to open. As 30 is the usual practice, the mechanism for operating the doors is interconnected with the shaft 14 to cause the step to unfold at the same time and as the passenger steps from the treadle onto the step the weight of the passenger causes the step to make a final movement of a very short distance so that the set screw 21 contacts with the lever 12 and causes it to raise a slight distance. As a result, the rod 11 contacts with the push button 8 and 35 maintains the switch in casing 7 closed so that the doors are maintained opened so long as anyone remains on the step. The rod 11 contacts with the push button 8 even though the treadle is returned to raised position. 40 When the step is cleared the adjustable engaging lever 20 drops away permitting the operating lever to drop down against the stop 23, causing the switch in casing 7 to open so that the doors are automatically closed.

45 It is apparent from the foregoing disclosure that I have devised a simple device for carrying out the objects of this invention involving certain principles which may be readily embodied in other forms by those skilled in the art without departing from the invention. I do not, therefore, desire to be limited to the exact disclosure given for purposes of illustration but rather to the scope of the invention as defined in the appended 50 claims.

What I seek to secure by United States Letters Patent is:

1. In a vehicle having doors thereon, the combination comprising a treadle plate pivotally mounted in the platform of the vehicle adjacent the doors, a switch completely mounted on the treadle, means for closing the switch when the treadle is depressed, a folding step mounted on the vehicle, and means operated by the step when a passenger is standing thereon for maintaining the switch closed when no passenger is standing on the treadle, said switch being completely supported by the treadle. 70

2. In a vehicle having doors and a folding step mounted thereon, the combination comprising a pivoted treadle plate mounted in the platform of the vehicle adjacent the doors, a single switch completely mounted on the treadle plate, means adjacent the switch for closing it when the treadle is depressed, and mechanism connected with the folding step for closing the switch when a passenger is standing on the folding step. 80

3. In a vehicle having doors therein, the combination comprising a depressible treadle in the platform of the vehicle adjacent the doors, a switch mounted on the underside of the treadle, a stop member supported under the treadle and adapted to engage and close 95 said switch when the treadle is depressed, a folding step, a vertically movable rod slidably engaging said stop member, and means on said step to engage said rod when fully extended and move it upwardly to close said switch when the treadle is in raised position. 100

4. In a vehicle having doors and a folding step thereon, the combination comprising a pivoted movable treadle plate mounted adjacent the doors and forming a part of the platform of the vehicle, a push button switch completely mounted on the underside of the treadle plate, flanged means adjacent the switch button adapted to close said switch upon the descent of said treadle plate, a folding step mounted on the vehicle, and a guided push rod adapted to extension through said flange means and to operation by the step when a passenger is standing thereon to maintain the switch closed when no passenger is 110 standing on the treadle. 115

In testimony whereof I have hereunto set my hand on this 4th day of May A. D., 1928.

ROSCOE D. CONKLIN.
